UNITED STATES PATENT OFFICE

2,370,391

GARMENT HANGER

John Bolten, Andover, Mass., and Henry Spitz,
Great Neck, N. Y.

Application November 27, 1943, Serial No. 511,932

6 Claims. (Cl. 223—92)

This invention relates to improvements in garment hangers of the type generally known as dress hangers, and the principal object of the invention is to provide a non-metalliferous hanger, that is, a hanger containing no metal, which will not stain or soil the garment by reason of rust, corrosion or by deterioration will stain, soil, or otherwise damage delicate fabrics which are supported upon it.

A further object of the invention is to provide a garment hanger construction which will wholly avoid the use of metal in view of the shortage of metal due to war conditions.

Some usual hangers comprise a curved supporting frame of wood or fibre composition which is centrally supported upon a metal suspending hook having a shank extending into or through the body of the hanger and fixedly secured to or rotatably mounted therein. Other types of hangers are formed wholly of metal wire bent into the desired form and having an integral metal hook extending upwardly from the central portion thereof and in which the hook is not rotatable with respect to the body of the hanger. Still other hangers are made of cardboard or other fibrous material with an integral hook which is not rotatable relatively to the hanger body. It is desirable, if not essential, that the suspending hook be rotatably mounted in the body of the hanger in order that the hanger and the garment thereon may be hung upon a support which is not at right angles to the plane of the body of the hanger, and a further object of the invention is to provide a hanger having a non-metal hook provided with a rotatable connection to the body of the hanger.

More particularly the invention relates to improvements in hangers formed of plastic, preferably thermoplastic, material and in which the suspending member is also of plastic material and the shank of which is secured against withdrawal from the body by non-metallic preferably plastic material.

A further object of the invention is to provide a garment hanger which will present smooth curved surfaces to support the garment and prevent wrinkles thereof and which will present no splinters or rough surfaces which would snag or abrade the fabric supported upon them and which is of such material as to avoid deterioration which might stain or soil or otherwise damage such delicate fabrics.

These and other objects and features of the invention will more fully appear from the following description and the accompanying drawing

and will be particularly pointed out in the claims.

A preferred embodiment of the invention is illustrated in the accompanying drawing, in which,

Fig. 1 is a side elevation of a hanger embodying the invention, a portion of the body being broken away and lined to show that it is of plastic composition;

Fig. 2 is a view partly in vertical section illustrating the body and shank both of plastic material and the means for preventing the shank from being withdrawn from the body;

Fig. 3 is a sectional view on lines 3—3 Fig. 2; and,

Fig. 4 is an enlarged detail view more clearly illustrating the elastic split ring which embraces a circularly recessed portion of the shank of the hook to prevent its withdrawal from the body of the hanger.

10 The preferred embodiment of the invention illustrated in the drawing comprises improvements upon the constructions disclosed in our prior Letters Patent No. 2,310,058 granted February 2, 1943, and No. 2,318,664 granted May 11,

15 25 1943, each of which discloses a garment hanger the body of which is formed of plastic material and a suspension member in the form of a hook having a metal shank mounted centrally in the neck portion of the hanger and extending trans-

30 versely across an aperture in the thin web of the hanger and journaled at its lower end in the body of the hanger with the deformity in the metal shank abutting the upper wall of the aperture to prevent withdrawal of the shank of the suspen-

35 sion member from the body of the hanger. The present invention is similar in general construction to those disclosed in our previous patents but differs therefrom in that the hook shaped sus-

40 pension member which is of plastic material has a shank of plastic material, integral with that of the hook shaped portion, which extends centrally through a portion of the body of the hanger into the aperture and is provided with non-metalliferous means for preventing withdrawal of the

45 shank from the body of the hanger. Obviously the shank may extend entirely through the body of the hanger and may be similarly provided with a non-metalliferous means for preventing withdrawal of the shank from the body.

50 The hanger illustrated in the drawing comprises an integral body of plastic, preferably thermoplastic, material having a thin wide web 1 with a central neck portion 2 preferably provided with a central aperture 3 and outwardly and downwardly curved arms 4 and 5 extending in

opposite directions from the neck portion. The body also comprises an upper peripheral rib 6 of greater thickness, preferably at least three times the thickness of the web, which presents a smooth gently curved upper surface for supporting the shouldered portions of the garment and is provided centrally of the neck portion with a downwardly extending boss 7 which terminates at the upper end of the aperture 3. The body desirably also is provided with a lower peripheral rib 8 which desirably is of less thickness and the central portion thereof desirably has a thickened reinforcing boss 9 in axial alinement with the boss 7 to strengthen the apertured neck portion of the hanger. The arms of the garment hanger may if desired be provided with downwardly and outwardly inclined recesses 10 bounded by the thickened rib 6 to receive the shoulder straps of ladies' dresses or slips so constructed as to prevent them from slipping off the ends of the hanger but to permit them to be removed easily from the hanger.

The suspension mechanism comprises a hook-shaped member 11 of integral plastic, preferably thermoplastic, material having an integral straight extension or shank 12 which is preferably rotatably mounted in a vertical aperture or bearing extending through the rib 6 and boss 7 and having a rounded or tapering end portion 13 which projects below the upper wall of the aperture 3. However if desired the shank may be of sufficient length to extend through and similarly journaled in the boss 9 with the extension thereof projecting below the lower wall of the boss. The extended or exposed portion of the shank is provided with a circumferential groove or channel 14 (Figs. 3 and 4) and an elastic expansible split ring 15 of greater diameter than the shank of the suspension member is sprung into this groove thereby providing an abutment to prevent withdrawal of the shank from the bearing in the boss or bosses in which the shank of the hook is mounted.

By reason of the present construction the body of the hanger and the suspending member can be packaged economically in unassembled condition in a much smaller package for storage and shipment and upon removal from the container readily assembled in operative position, thereby not only saving considerable storage space, but also preventing the liability of breakage of the suspending member by the bending of the portion of the package into which the suspending member would otherwise project if the suspending member were assembled upon the body. Desirably an insert 16 of like plastic material may be deposited in or integrally connected to the adjacent ends of the split ring by a suitable solvent thereby providing a continuous integral ring for preventing withdrawal of the shank of the hook.

By reason of the construction above described a hanger is provided which contains no metal, which is subject to corrosion, and in the construction described the exposed end portion of the shank and the retaining ring are within the recesses in the neck portion of the hanger and present no sharp edges, roughness or points which are liable to snag delicate fabrics which are supported by the hanger. The same will be true if the shank of the hanger extended across the aperture and through the lower boss 9 as the locking ring and the rounded end of the shank would not present any edge or surface which

would be likely to injure the fabric supported upon the hanger.

It will be understood that the particular embodiment of the invention shown and described herein is of an illustrative character and that the suspending member may be made of any suitable non-metalliferous material throughout and that any suitable non-metalliferous means may be provided for preventing withdrawal of the shank of the suspending member from the body of the hanger within the meaning and scope of the following claims.

Having thus described the invention, what is claimed as new, and desired to be secured by Letters Patent, is:

1. A garment hanger comprising a non-metalliferous body having downwardly curved arm portions extending in opposite directions from the central portion thereof and a non-metalliferous hook-shaped suspending member having an integral shank mounted in and extending through the central portion of said body and having a circumferential recess in the exposed end thereof and a split ring of elastic plastic material and of greater diameter than said shank sprung into said recess acting to prevent withdrawal of the shank of the suspending member from the body of the hanger.

2. A garment hanger comprising a non-metalliferous body having downwardly curved arm portions extending in opposite directions from the central portion thereof and a non-metalliferous hook-shaped suspending member having an integral shank mounted in and extending through the central portion of said body and having a circumferential recess in the exposed end thereof and a split ring of elastic plastic material and of greater diameter than said shank sprung into said recess with the adjacent ends of said split ring united by plastic material to form a continuous integral ring for preventing withdrawal of the shank of the suspending member from the body of the hanger.

3. A garment hanger comprising a body of thermoplastic material having a neck portion and outwardly and downwardly curved arms extending in opposite directions therefrom, and a hook-shaped suspension member entirely of plastic material having a straight shank extending centrally through said neck portion provided with a recess in the exposed end thereof and plastic means releasably secured to the exposed end portion of said shank in said recess to prevent withdrawal thereof from the body of the hanger when in assembled position, but to permit detachment of the suspending member for economy and safety in packaging and transportation.

4. A garment hanger comprising an integral body of plastic material having a neck portion, and outwardly and downwardly curved arms extending in opposite directions therefrom and having a thin web provided with a vertical aperture centrally of said neck portion and having an upper peripheral rib of greater thickness than the thickness of said web presenting a smooth curved supporting surface for the garment and having a central boss extending to said aperture, a hook-shaped suspending member entirely of plastic material having a shank journaled in and extending vertically through said boss and having a cylindrically recessed end portion projecting into said aperture, and a split ring of elastic plastic material of greater circumference than said shank mounted in said cylindrical recess acting to pre-

vent withdrawal of the shank from the body of the hanger.

5. A garment hanger comprising an integral body of plastic material having a neck portion, and outwardly and downwardly curved arms extending in opposite directions therefrom and having a thin web provided with a vertical aperture centrally of said neck portion and having an upper peripheral rib of greater thickness than the thickness of said web presenting a smooth curved supporting surface for the garment and having a central boss extending to said aperture, a hook-shaped suspending member entirely of plastic material having a shank journaled in and extending vertically through said boss and having a cylindrically recessed end portion projecting into said aperture, and a split ring of elastic plastic material of greater circumference than said shank mounted in said cylindrical recess and having its ends integrally united by plastic material to 20 form a complete ring acting to prevent withdrawal of the shank from the body of the hanger.

6. A garment hanger comprising a body of thermoplastic material having a neck portion provided with a vertical central boss and outwardly and downwardly curved arms extending in opposite directions from said neck portion, a hook-shaped suspension member entirely of plastic material having a straight shank extending centrally through and beyond said central boss and provided with an annular recess in the exposed end thereof, a split ring of elastic material of greater external diameter than said shank sprung into said recess acting to prevent withdrawal of the shank of the suspending member from the body of the hanger when in assembled position but detachable from said shank by spreading the adjacent ends of the ring, thus enabling the suspension member to be detached from the body and economically packaged with the body for storage and transportation.
